Margaret Michelson, New York, N. Y.

Application July 21, 1937, Serial No. 70,554

Term of patent 3½ years

To all whom it may concern:

Be it known that I, Margaret Michelson, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The characteristic feature of my design resides in the combination on the dress as shown of the graduated gores, which are fitted at the hip-line, in association with the shirring at the inner armhole portion, as shown.

I claim:

The ornamental design for a dress, substantially as shown and described.

MARGARET MICHELSON.
